HANDLE FOR A NOZZLE

Benjamin Sosnick, San Jose, Calif.

Application May 26, 1958, Serial No. 51,088

Term of patent 14 years

(Cl. D91—3)

FIG. 1

FIG. 2

FIG. 3

Figure 1 is a perspective view of a handle for a nozzle showing my new design;

Figure 2 is a reduced top plan view thereof; and

Figure 3 is a side elevational view thereof.

I claim:

The ornamental design for a handle for a nozzle, as shown.
